SEPARATION OF VALUABLE PRODUCTS
FROM MIXTURES THEREOF WITH SOLID
SUBSTANCES

Rudolf Wietzel, Ludwigshafen-on-the-Rhine, Germany, and Bruno Engel, Stockholm, Sweden, assignors to I. G. Farbenindustrie Aktiengesellschaft, Frankfort-on-the-Main, Germany, a corporation of Germany

No Drawing. Application May 23, 1928, Serial No. 280,114, and in Germany June 1, 1927

12 Claims. (Cl. 196—13)

This invention relates to the recovery of valuable hydrocarbons and oils from mixtures thereof with solid substances, and to the production of the said hydrocarbons and oils from carbonaceous materials.

5 We have found that such hydrocarbons and oils may be recovered with particular advantage from mixtures thereof with solid substances, in particular from the crude solid or pasty products obtained by low temperature carbonization, cracking and extraction of carbonaceous materials, and in the destructive hydrogenation of coals, tars, mineral oils and the like, which consist of mixtures of oils and other valuable hydrocarbons with solid substances such as carbonaceous residues, ash constituents, or other solid admixtures such as catalysts, by stirring the mixture, preferably at a slightly elevated temperature, with a liquid in which the oil is insoluble, or only slightly soluble, and to which an alkaline reaction has been imparted and which contains small amounts of a wetting or emulsifying agent, such as sulfonic acids of aromatic or aliphatic hydrocarbons, in particular nucleo-25 alkylated sulfonic acids of aromatic hydrocarbons, cellulose pitch, saturated or unsaturated fatty acids, their salts and derivatives, glue, saponines, dextrine, oxidation products of paraffins, and the like. Products obtained by sulfo-30 nating products of the destructive hydrogenation of coal, tars and the like are also suitable.

When the adhesion between the solid substances and the oils has been sufficiently loosened, the oil is separated in various ways, as for example mechanically, as by centrifugal means, preferably in the warm, or by means of electric or magnetic fields, or in other suitable ways, or by the application of several methods of separation simultaneously.

40 The process may be applied alone or in combination with other methods, such as subsequent low temperature carbonization, or extraction and the like; and the mixtures may also be subjected to repeated treatment and to the action of different kinds of liquids. The conditions in respect of pressure and temperature may be varied within wide limits according to the character of the substances under treatment.

50 Materials suitable for treatment comprise, for example, the residues from the distillation of tar, cracking residues, crude mineral oils, the residues from the extraction of coal and the like, or the residues obtained in the heat treatment under pressure, with or without hydrogen, of

coals, peat, cellulose, tar, oils, bitumen or other carbonaceous substances.

It has also been found suitable, in treating the oleaginous sludge, to employ solutions which also contain salts such as chlorids, sulfates and the like. If the concentration of these be such that the specific gravity of the solutions is equal to, or greater than that of the solids to be separated, it is easy to carry on the operations, for instance the centrifuging, continuously. 65

In centrifuging especially, there is no need to stir up the sludge under treatment with the added liquid beforehand in a special stage of the process, but the material under treatment and the added liquid may be introduced simultaneously 70 into the separator, such as a centrifuge. This not only saves one working stage, but also, in certain circumstances, leads to a better separation of the oil and solid residue. The rate of separation of the material on the one hand, and 75 the added liquid on the other, depends on the character of the former.

The amount of emulsifying and wetting agents to be added is usually very small, for example 0.05 per cent or sometimes still less. The optimum 80 quantity depends on the character of the material under treatment in each case. The other working conditions, such as temperature, speed of the centrifuge and the like, also depend on the material under treatment and on the wetting agent 85 used, and must be determined by experiment in each case. For example, in centrifuging a coal sludge, such as is obtained, for example, in the extraction of coal with solvents under pressure, it is preferable to work at a temperature not exceeding 100° to 110° C. when an equal quantity of 90 an 0.05—0.1 per cent aqueous solution, for example of alkylated naphthalene sulfonic acids, is added to the sludge during the centrifuging process. 95

The added liquid after being freed from oil by centrifuging may be used over again.

The employment of the said substances adapted to reduce the surface tension, especially the emulsifying and wetting agents, for example the organic substances which contain the radicle of a mineral acid in the molecule, such as aromatic and aliphatic sulfonic acids, their derivatives, and substitution products, is not restricted to the separation of oils from mixtures with solid substances, but also offers great advantages in carrying out the destructive hydrogenation, cracking and extraction under pressure of species of coal, tars, mineral oils and other carbonaceous products, or several of these processes combined, since 105 110

excellent yields of valuable, and especially liquid hydrocarbons are obtained.

These processes are hereinafter referred to for the sake of brevity as the production of valuable products by heat treatment of carbonaceous materials. The liquid employed in this case need not necessarily be rendered alkaline, although in some cases, this may be advantageous.

This process is especially adapted for the extraction of any kind of coal, under pressure, with liquid organic solvents, comprising a great variety of substances (especially those of high boiling point range), and particularly fractions or transformation products of mineral oils or tars, such as cresols, xylene, naphthalene, anthracene oil, hydrogenation products of naphthalene or benzene, or mixtures of benzene and alcohol or halogenated hydrocarbons and the like.

The process may also be employed with advantage in the destructive hydrogenation, and also in cracking, since the said additions exert a splitting action on the hydrocarbons and the like.

The operation may be conducted under high pressures, such as 200 atmospheres, and when required, with special addition of hydrogen or other gases, and also at pressures as low as about 50 atmospheres, in which event the excess pressure generated under certain conditions by the liberation of gases from the coal, is released.

If the operation be carried on in the presence of hydrogen, a portion of the coaly substance passing into solution is hydrogenated, especially at temperatures about 400° C.

In addition to the substances added to reduce the surface tension of the resulting liquid products, other inorganic or organic substances, such as alkalies, zinc oxid, magnesia and the like, may also be added.

The following examples will further illustrate the nature of the said invention which however is not restricted thereto. The parts where not otherwise stated, are by weight.

Example 1

If a 40 to 50 per cent solution of calcium chlorid, to which is added 0.08 per cent of sodium isopropylnaphthalene sulfonate be admitted into a separating drum at the rate of 6 liters per second, and the sludge, (containing about 20 per cent of solids) to be separated (obtained by extracting brown-coal with tar oils under pressure) be admitted at the same time, and at the same or rather slower rate, both liquids being at a temperature which is not below 100° C. and the separator being run at 7000 revolutions per minute, a practically ash-free oil is obtained as well as a residue still containing about 9 to 12 per cent of oil.

If the added liquid be slightly acidified with a mineral acid, for example hydrochloric acid, a residue richer in oil and also an oil, richer in residue (about 4 to 6 per cent) is obtained. On the other hand, if the added liquid be rendered merely faintly alkaline, by the addition of 0.3 to 1 per cent of caustic soda, an ash-free oil is obtained, together with a residue which contains only 4 to 6 per cent of oil, or still less in some cases. The added liquid remaining adherent to the centrifuged solid residue, may be readily removed by pressing and the like. The washing liquid is continuously recovered in circulation.

Example 2

A mixture of oil and carbonaceous material obtained by the destructive hydrogenation of

lignite is treated in a centrifuge with an equal amount of a weakly alkaline aqueous solution of 0.2 per cent strength of a product which is obtained by the oxidation of solid paraffin. Besides the oil, a residue is obtained containing 25 per cent of products soluble in benzene. If the aforesaid product of the destructive hydrogenation is centrifuged with an addition of alkali alone, a residue is obtained containing 40 per cent of substances soluble in benzene. If the centrifuging of the mixture of oil and carbonaceous material is carried out without any addition at all, a residue containing 50 per cent and even more of benzene soluble products is obtained. By means of suitable devices, for ejecting the material, for example by means of worm conveyors arranged within the centrifuge, the residue may be removed continuously.

Example 3

A mixture of oil and carbonaceous material as described in Example 2 is triturated in a vessel fitted with a stirrer having a high speed of rotation with 5 times the amount of an aqueous weakly alkaline solution of Turkey red oil of 0.2 per cent strength. The emulsion thus obtained is passed into a large vessel in which separation gradually takes place. The carbonaceous sludge which is poor in oil collects at the bottom of the vessel and is then filtered off by suction. The upper layers which comprise an emulsion of oil in water are filtered off separately. In a further vessel the emulsion is destroyed by acidulating moderately and the oil which then collects on the surface of the aqueous solution may be collected and is pure.

By repeating the treatment of the carbonaceous sludge which settles down at the bottom of the vessel, over 80 per cent of the oil contained therein, can be recovered. The last traces of oil, can be removed by the aid of solvents. When operating without an addition of alkali, only 40 per cent or less of the oil can be obtained under otherwise similar conditions of working.

What we claim is:—

1. A process for the recovery of hydrocarbon oils from a mixture thereof with solid substances obtained in a process of thermally converting carbonaceous materials, which comprises forming a substantially stable emulsion of said oils in an added aqueous solution of a wetting and emulsifying agent in which solution said solid substances are insoluble and, to which solution an alkaline reaction has been imparted by an addition of alkali, and separating the solids from the liquids.

2. A process for the recovery of hydrocarbon oils from a mixture thereof with solid substances obtained in a process of thermally converting carbonaceous materials, which comprises forming at a slightly elevated temperature a substantially stable emulsion of said oils in an added aqueous solution of a wetting and emulsifying agent in which solution said solid substances are insoluble and, to which solution an alkaline reaction has been imparted by an addition of alkali, and separating the solids from the liquids.

3. A process for the recovery of hydrocarbon oils from a mixture thereof with solid substances obtained in a process of thermally converting carbonaceous materials, which comprises forming a substantially stable emulsion of said oils in an aqueous solution of a salt and of small amounts of a wetting and emulsifying agent in which solution said solid substances are insoluble.

- ble and, to which solution an alkaline reaction has been imparted by an addition of alkali, and separating the solids from the liquids.
4. A process for the recovery of hydrocarbon oils from a mixture thereof with solid substances obtained in a process of thermally converting carbonaceous materials, which comprises emulsifying said oils in an added aqueous solution of a wetting and emulsifying agent in which solution said solid substances are insoluble and, to which solution an alkaline reaction has been imparted by an addition of alkali, and separating the solids from the liquids, the said process being rendered continuous by freeing the added liquid from the bulk of the oils and hydrocarbons and returning it to the process.
5. A process for the recovery of hydrocarbon oils from a mixture thereof with solid substances obtained in a process of thermally converting carbonaceous materials, which comprises introducing said mixture into a centrifuge simultaneously with an aqueous solution containing a small amount of a wetting and emulsifying agent in which solution said solid substances are insoluble and, to which solution an alkaline reaction has been imparted by an addition of alkali, thus forming a substantially stable emulsion of the hydrocarbon oils in the aqueous liquid and centrifuging the solid products off.
10. A process for the recovery of hydrocarbon oils from a mixture thereof with solid substances, said mixture being obtained in the destructive hydrogenation of carbonaceous materials, which comprises forming a substantially stable emulsion of said oils in an added aqueous solution of a wetting and emulsifying agent in which solution said solid substances are insoluble and, to which solution an alkaline reaction has been imparted by an addition of alkali, and separating the solids from the liquids.
11. A process for the recovery of hydrocarbon oils from a mixture thereof with solid substances obtained in a process of thermally converting carbonaceous materials, which comprises forming a substantially stable emulsion of said oils in an added aqueous solution of a nucleoalkylated aromatic sulfonic acid in which solution said solid substances are insoluble and, to which solution an alkaline reaction has been imparted by an addition of alkali, and separating the solids from the liquids.
12. A process for the recovery of hydrocarbon oils from a mixture thereof with solid substances obtained in a process of thermally converting carbonaceous materials, which comprises emulsifying said oils in an added aqueous solution of sodium isopropyl naphthalene sulfonate in which solution said solid substances are insoluble and, to which solution an alkaline reaction has been imparted by an addition of alkali, and separating the solids from the liquids.
